OIL BURNER FOR TOBACCO DRYING
AND CURING MEANS

William B. Dowless, Abbottsburg, N. C.

Application June 28, 1951, Serial No. 234,042

1 Claim. (Cl. 158—53)

1

This invention relates to an oil burner for tobacco drying and curing means and is an improvement over the structure shown in my Patents No. 2,223,301, dated November 26, 1940, and No. 2,444,814, dated July 6, 1948.

An object of this invention is to provide an improved burner for tobacco drying and curing means which is of simple construction so that it can be easily and cheaply made and will provide a minimum of parts in order that the burner will not readily get out of order.

With the above and such other objects in view, as may hereinafter more fully appear, the invention consists of the disclosed novel construction, combination and arrangement of parts, but it will be understood that changes, variations and modifications may be resorted to which fall within the scope of the invention, as claimed.

In the drawings:

Figure 1 is a detail elevation of a fuel supply tank on the exterior of the housing for a burner of this character.

Figure 2 is a vertical sectional view taken on the center line of the burner.

Figure 3 is an enlarged sectional view taken on the line 3—3 of Figure 2.

Figure 4 is an end elevational view of the burner.

Figure 5 is a vertical section through the regulating valve on the fuel tank.

Referring to the drawings, a burner or heating means is generally designated as 11. The heating means 11 includes a hot air duct 12.

The two hot air pipes 12 each have heating members 18 secured to one end thereof, the heating members 18 being of like construction, and shown in greater detail in Figures 4, 5 and 6.

Each heating member 18 is formed of upper and lower semi-cylindrical members 19 and 20 having complementary end walls 21 and 22. The semi-cylindrical members 19 and 20 are each provided with pairs of confronting ears 23 and 24, respectively, which are secured together by means of fastening members 25. The burner 18 is supported by means of a base structure generally designated as 26 which includes a base plate 27 and a pair of upstanding supporting plates 28 having concave seats 29 on the upper edges thereof within which the burner 18 is adapted to engage.

The lower burner member 20 is provided with an upwardly offset circular boss 30, Figure 5, and the lower side of the boss 30 is flattened as indicated at 31. The boss 30 forms a support or seat for a nozzle generally designated as 32. The nozzle 32 is formed of a disc-shaped bottom wall

33, an annular side wall 34, and a disc-shaped top wall 35. A plurality of upwardly and outwardly inclined openings 36 are formed in the side wall 34 and provide a means whereby the fuel will be directed upwardly and outwardly.

The burner head or member 32 has a nipple 37 threaded thereinto which extends through the center of the boss 30, and the lower end of the nipple 37 has one end of a fuel supply pipe 38 connected therewith. A washer or gasket 39 is interposed between the fuel connection 38 and the flat lower side 31 of the boss 30. A sealing means 40 is interposed between the bottom wall 33, and the upper side of the boss 30. The bottom wall 33 is formed adjacent the outer margin thereof with a circular bead 41 which provides a means whereby any oil flowing downwardly over the side wall 33 will be directed outwardly from the boss 30. As shown in Figure 5 the boss 30 is substantially 20 smaller in diameter than the diameter of the bead 41, and the outer surface of the boss 30 is formed on a concave 42 so as to guide the overflowing oil 15 outwardly and into an annular trough or channel 43 which is formed in the lower burner member 20 25 about the boss 30.

A rearwardly extending trough or groove 44 communicates with the trough 43, and a drainpipe 45 communicates at one end with the trough 44, and pipe 45 is adapted to be extended to a point 30 exteriorly of the housing 10. Air is fed into the burner 18 through an air intake pipe 46 which extends through the burner member 19 and depends over the burner head 32.

The lower end of the intake pipe 46 has a diametrically disposed tubular bar 47 fixed therein which is formed with an opening 48 within which a conical projection 49 carried by the top wall 35 of the burner head is adapted to engage. The lower burner member 20 is provided on the interior thereof with a transversely disposed and inverted V-shaped projection 50 which forms a dam to prevent any overflowing oil within the burner 18 from flowing forwardly into the hot air duct 12.

The duct or pipe 46 for conducting air through 45 the burner 18 includes an extension 51 which extends to a point exteriorly of the housing 10. The fuel supply pipe 38 is extended beneath the housing 10 to a point exteriorly thereof and includes a vertical riser 52 having a cup-shaped or funnel member 53. A fuel regulating valve member 54 is disposed above the cup or funnel 53 and includes a needle valve 55 having a pointer 56 secured thereto above the top wall 57 of the valve housing and the upper side of the top wall 57 as shown in 50 Figure 7 is formed with graduations 58.

The valve member 54 is connected to a horizontally disposed pipe 59 which extends from the lower portion of a fuel supply tank 60. The tank 60 is disposed on the exterior of the housing 10.

In the use and operation of this heating means the needle valve 55 is open so that the fuel will drip into the funnel or cup-shaped member 53 and will then gravitatively flow to the burner head 32. Initially, the fuel will flow from the burner head into the trough 43, and the fuel is lighted through an opening 61 formed in the end wall 22 of lower member 20 which is normally closed by a closure plate 62. When the burner head 32 becomes hot the fuel will vaporize and the flames will then be directed upwardly in substantially an inverted conical configuration across the lower end of the air intake pipe 46.

The heat from the burner 18 will flow through the duct 12, and will then exhaust through an appropriate outlet.

What is claimed is:

A burner for use in tobacco curing systems comprising a cylindrical housing closed at one end and open at the other end, said housing being formed of complementary upper and lower semi-cylindrical members, confronting pairs of ears carried by said members, means securing said ears together, an upwardly offset circular boss carried by said lower member, a fuel nozzle seated on said boss,

said nozzle being formed of a hollow disc-shaped body having upwardly and outwardly directed openings, said nozzle being greater in diameter than said boss and having a marginal bead extending downwardly from the bottom thereof and overhanging the boss, said lower member having an annular channel formed therein outwardly of said boss and below said nozzle, said channel being greater in diameter than said nozzle, overflow pipe means connected to said channel, said boss being downwardly and outwardly flared to conduct the oil drippings from said bead to said channel a raised dam extending transversely across the interior of said lower member between said burner and said open end, said dam being of a height substantially equal to the height of the top of said burner, an air intake pipe extending through said upper member in alignment with said nozzle and terminating above the latter, and a fuel supply line connected with said nozzle.
